Enoch T. Larrabee
his ATTORNEY.

UNITED STATES PATENT OFFICE.

WILLIAM HEPNER, OF LOS ANGELES, CALIFORNIA.

HAIR STRUCTURE.

Application filed September 28, 1926. Serial No. 138,177.

My invention relates to hair structures that are worn principally by women and preferably employ a permanently bobbed style of hair.

5 An object of my invention is to construct a hair structure in such a manner that it can be made cheaply and substantial and which can be readily applied to the head of the wearer.

10 An object is to provide a simple, novel and inexpensive hair structure which may be used in combination with a hat to change the color of the wearer's hair to observers.

An object is to provide a novel hair structure that shall be capable of positive mounting on any of a variety of shapes and sizes of heads, and which may be quickly placed in position and removed therefrom, and that will effectively fit the head of the wearer so 20 as not to be distinguishable from the natural hair.

Another object is to provide a device of the above character that may be fitted to the head without requiring the usual variety of 25 measurements and painstaking adjustments.

Another object is to provide in a device of this character novel means for securely and firmly holding the hair structure in place on the wearer's head.

30 At present in many instances women are bobbing their hair in such abbreviated styles, or to such extremes, or have such thin hair or high foreheads or are bald that when a hat is worn by such person there is not 35 sufficient hair remaining to show from under the hat around the temples and over the forehead; and an object of this invention is to provide simple means to overcome the above results which many times are objectionable.

40 Another object is to provide a novel and simple hair structure which, when worn by women whose natural hair has been closely cut, will supply sufficient hair over the ears and temples so as to give with the natural 45 hair of the wearer a highly desired and satisfactory appearance without being distinguishable from the natural hair.

In practicing my invention I provide a 50 relatively long and narrow foundation to which hair strands are attached and which foundation is of such length as to span the forehead of the wearer from approximately temple to temple, in combination with simple

fastening means attached to the ends of the foundation and which is adapted to be covered by the natural hair so as to be entirely concealed from view when the device is in place. 55

Other objects, advantages and features of invention may appear from the accompanying drawings, the subjoined detail description, and the appended claims. 60

The accompanying drawings illustrate the invention in the form I at present deem preferable but showing several modes of hair 65 dress.

Figure 1 is a more or less diagrammatic view of a device embodying my invention as applied to a head, the natural hair of which 70 has been closely cut.

Fig. 2 is a view of the device shown in Fig. 1 as applied to the head and worn in conjunction with a hat.

Fig. 3 is a bottom plan view of the foundation and fastening means of the device 75 shown in Figs. 1 and 2.

Fig. 4 is a more or less perspective view on enlarged scale of one end of the fastening means before attachment to the base or foundation of the hair structure. Portions 80 are broken away to disclose interior construction.

Fig. 5 is a more or less diagrammatic view of a device constructed in accordance with my invention and showing a modified form 85 of hair dress.

Fig. 6 is a bottom plan view of the device shown in Fig. 5.

Fig. 7 is a view showing a different style 90 of hair dress.

Fig. 8 is a bottom plan view of the device shown in Fig. 7.

My invention comprises in general a device A which is adapted to provide sufficient hair over the forehead and temples particularly 95 on women who have thin hair or high foreheads or are bald, or who have grey hair, or who have had their natural hair cut close to the head; or to immediately give those who desire the appearance of having their 100 hair in a dressed and wavy condition by merely applying a simple and light device of this character and combing out the hair on the same so that the strands of hair thereon intermingle with the natural hair, and 105 when this is done and the hair on the device

matches the natural hair the additional or false hair cannot be distinguished from the natural hair.

The device A shown in Figs. 1-3 comprises 5 a relatively long and narrow hair supporting foundation or base 1 of sufficient length to span the forehead along the hair line from approximately temple to temple. The foundation 1 may be of any suitable material 2, 10 such as silk or net usually used in forming a ventilated foundation for hair structures and to which bodies or strands of hair 3 are attached and extend from all parts of one side of said base portion in any suitable manner. In this device I have shown what is 15 generally termed as a ventilated parting.

The foundation 1 is bordered by a band 4 of suitable material and a plurality of relatively stiff cross members or stiffeners 5, in 20 the form of flat springs, extend crosswise of the foundation from longitudinal edge to longitudinal edge thereof. The stiffeners 5 are covered by a strip 6 of suitable material and said stiffeners serve to maintain the longitudinal edges of the foundation in spaced 25 relation to each other.

Other stiffeners 7 extend across the ends of the base or foundation 1 at substantially 30 45 degree angles to assist in maintaining the shape of the device.

Flexible fastening means 8 which is preferably in the form of a substantially non-expansive and flexible string or cord 9 that has flexible and expansive members 10 preferably secured to each end thereof form simple and novel means for securely and firmly holding the foundation in place on the wearer's head.

The members 10 may be made as shown 40 in Fig. 4, by bending a piece of silver elastic 11 upon itself and securing the free ends of said elastic to a tape 12 or other suitable covering by stitches 13. The looped end of 45 said elastic is secured to one end of string 9 by means of stitches 14 encircling a knot 15 tied in string 9. The covering as shown in the form of a tape 12 may be folded upon itself as shown in Fig. 4 and the longitudinal edges thereof are stitched together by 50 stitches 16 to form a tunnel which is gathered over the elastic 11 to provide for expansion of the elastic and to also form a covering therefor so that the fastening means 55 will be neat appearing. The string or cord 9 extends through the tape at the looped end 17 which is folded over knot 15 and secured to the tape so as to entirely conceal the fastening of the cord to the elastic. The free ends 18 of tape 12 are attached to the foundation 2 at the ends thereof by stitches 19.

Although I have shown the expansive members 10 constructed as shown in Fig. 4, I do not wish to be limited to the exact arrangement of the parts therein shown, as it 65 is apparent that the silver elastic 11 may be

turned end for end in the tunnelled tape or the looped end of the tape may be secured to the foundation and the free ends 18 folded over knot 15, without departing from the spirit of my invention.

When the device is in position on the head of a wearer the fastening means extend beneath the under rear side of the head and is adapted to be covered and concealed by the natural hair of the wearer which is combed out to cover the string 9 and the expansive members 10.

In practice the fastening means are made of the desired length to fit the head of the person onto which the device is to be 80 mounted; and in order to place the device in position the foundation is placed on the head along the hair line of the forehead and the string 9 is slipped down over the back of the head, and it as well as the members 10 85 may be entirely concealed from view by combing the hair on the foundation and/or the natural hair thereover as the case may be. The expansive members 10 afford sufficient expansibility for the string 9 to be pulled 90 over the prominent part of the head and also hold the device snugly on the head without undue strain or discomfort to the wearer.

With the foregoing construction I provide a device that may be easily and quickly attached to the head and which will materially improve the wearer's appearance as it will be apparent that women who are troubled with grey hair along the forehead and temples will not have to resort to dyeing of the hair to make it of one uniform color, because by applying my device it will satisfactorily cover such grey hair so as not to be visible to observers or if considerable grey hair is present by applying my device 105 such grey hair will not be visible to observers when a hat is worn.

In some instances a person may have had the natural hair cut close to the head and also be provided with several hats that fit the head of such person, and by wearing my hair structure a desired effect of having an abundant growth of hair which is visible in conjunction with a hat is obtained without increasing the head size so as to require 110 larger sized hats by the wearer as is the case when a wig or transformation is worn.

From the foregoing it is apparent that if a device of this character is worn in conjunction with a hat the wearer can easily 115 change the appearance of her hair light to dark or vice versa.

In Figs. 5 and 6 I have shown a slight modification of the base structure 1' by adding a forward extension 20 that has strands of hair extending therefrom and by such slight addition to the base structure the hair may be dressed to give a pompadour effect as shown in Fig. 5. The base in this form is 125 partially made of net but it is understood 130

that any suitable material may be used. The strands of hair 3' attached to base 1' extend from the sides or ends of the base in the same manner as in Figs. 1-3 and also 5 extend or flow rearwardly therefrom as shown in Fig. 6. The rearwardly extending strands of hair only partially cover the top part of the head, terminating a slight distance short of the crown of the head and 10 the securing cord 9 when in place and are adapted to be combed into the natural hair of the wearer so as to be worked thereinto and the false hair is then indistinguishable therefrom in the event of a close match with 15 the natural hair.

In Figs. 7 and 8 I have shown a still further modification of the contour of the base structure 1'' and have added at the parting of the device an extension 21 whereby I obtain 20 a drawn parting in a device of this character and provide simple, light and inexpensive means for obtaining such a parting and additional hair to cover the top part of the head. The extension 21 is a long and 25 narrow hair supporting member that extends rearwardly from the base and it is apparent that the relatively small size of such member will not add materially to weight or cost of my device. The strands of hair 3'' are usually combed into the natural hair of the wearer when the device is worn so as to be indistinguishable therefrom as in the case with the devices shown in Figs. 1-6.

35 From the foregoing it is apparent that by use of my device I provide means whereby the wearing of wigs is avoided in order to change the style of hair dress.

The strands of hair attached to the base 40 or foundation are preferably of a texture that may be dressed in what is termed a Marcel wave that is usually permanently formed therein and regardless of handling of the device or crumpling the device or 45 carrying the same in a purse or pocket, by merely combing out the strands of hair the device will have the appearance of always being in a dressed condition. This affords a light, neat appearing device that cannot 50 be detected by the public from the natural hair of the wearer, and which may be easily and quickly applied, combed out, and give the wearer the appearance of having the hair in a dressed condition without requiring 55 the delays and inconvenience incident to going to the hair dressers.

I claim:

1. A hair structure comprising a relatively long and narrow foundation member 60 adapted to span the forehead along the hair line from approximately temple to temple; strands of hair extending from all parts of one side of said foundation member; and a flexible member attached to said foundation 65 and extending beneath the under rear side

of the head and adapted to be covered and concealed by the natural hair of the wearer.

2. A hair structure comprising in combination a relatively long and narrow base portion adapted to extend over the forepart 70 of the head along the hair line from approximately temple to temple; strands of hair attached to and extending from all parts of one side of said base portion and adapted to supply hair over the forehead and around 75 the temples of the wearer; and a holding strap attached to said base adapted with said base portion to encircle the wearer's head and to be covered and concealed by the 80 natural hair of the wearer.

3. A hair structure comprising a relatively long and narrow base portion adapted to span the forehead of the wearer along the hair line from approximately temple to temple; strands of hair extending from all 85 parts of one side of said base portion; and a plurality of relatively stiff cross members extending from longitudinal edge to longitudinal edge of said base portion.

4. A hair structure comprising a relatively long and narrow base portion adapted to span the forehead of the wearer along the hair line from approximately temple to temple; strands of hair extending from all 90 parts of one side of said base portion; and a plurality of relatively stiff cross members 95 extending from longitudinal edge to longitudinal edge of said base portion intermediate and at the ends of said base portion, said end cross members extending at substantially 100 45 degree angles to the longitudinal edges of said base.

5. A hair structure comprising a hair supporting foundation adapted to span the forehead from approximately temple to temple; 105 a narrow hair supporting member extending rearwardly from said foundation at the parting of the hair thereon; and a holding strap attached to said foundation adapted to hold said foundation in place on the head of the 110 wearer.

6. A hair structure comprising a relatively long and narrow hair supporting foundation; and fastening means attached to said foundation comprising a flexible relatively 115 non-expansile string and an expansible member.

7. A hair structure comprising a hair supporting foundation; and fastening means attached thereto adapted with said foundation 120 to encircle the head of the wearer and comprising a flexible string; an expansible member attached thereto and comprising an expansible unit; and a covering for said expansible unit.

8. A hair structure comprising a hair supporting foundation; and fastening means attached thereto comprising a relatively non-expansile string and an expansible member 125 attached thereto, said expansible mem-

ber comprising a piece of silver elastic folded to form a loop; a covering enclosing said silver elastic; and means securing the free ends and the looped end of said silver elastic to said covering.

9. A hair structure comprising a hair supporting foundation; and fastening means attached thereto comprising a relatively non-expansible string and an expansible member attached thereto, said expansible member comprising a piece of silver elastic folded to form a loop; a covering enclosing said silver elastic; means securing one end of said silver elastic to said covering; and means securing one end of said string to the other end of said silver elastic.

10. A hair structure comprising a relatively long and narrow base portion adapted to span the fore part of the head along the hair line from approximately temple to temple; strands of hair secured to said base portion and extending from all portions of one side thereof, said strands of hair extending from said base to supply sufficient hair over the temples of the wearer, and extending rearwardly therefrom and adapted to be combed with the natural hair of the wearer so as to intermingle therewith.

In testimony whereof, I have hereunto set my hand at Los Angeles, California, this 22nd day of September, 1926.

WILLIAM HEPNER.
